SPEED CHANGING DEVICE FOR PHONO-
GRAPH TURNTABLESEdward E. Collison and Emil Nyman,
Fort Wayne, Ind.

Application December 17, 1931, Serial No. 581,694

2 Claims. (Cl. 274—9)

This invention pertains to a phonograph turntable and particularly a variable speed drive therefor, for the purpose of accommodating said turntable to records to be reproduced at different speeds of rotation.

Phonograph records are produced ordinarily at a speed of 78 revolutions per minute (R. P. M.). Consequently, a phonograph turntable for proper reproduction of such record is geared to rotate at the same speed or R. P. M. It is, however, anticipated that records may be produced at a slower speed in order to reproduce a program of longer duration. Thus, for accommodating a longer program, a record may be made to rotate at a slower given speed, for instance, a speed of 33½ revolutions per minute (R. P. M.).

It is the purpose of this invention to provide a simple and practical structure for a turntable drive which the operator may manipulate so that when thrown into one position by a suitable lever or the like, the turntable will be driven at 78 R. P. M., while in another position at 33½ R. P. M.—or any other corresponding speeds.

The full nature of the invention will be more clearly understood from the accompanying drawing and the following description and claims:

Fig. 1 is a central vertical section through the turntable mounting and driving mechanism showing the turntable driven at minimum speed. Fig. 2 is the same as Fig. 1 with parts removed, showing the turntable driven at maximum speed. Fig. 3 is a section on the line 3—3 of Fig. 1.

In the drawing there is shown a base plate 10 for the mechanism, above which there is mounted a rotatable turntable 11 having a record centering pin 12 for receiving a disk record 13 for reproduction. The turntable is driven through suitable mechanism as hereinafter described by an electric motor 14, said mechanism and motor being supported by a framework 15 depending from the base 10 or otherwise supported in association therewith.

Suitable reproducing mechanism in the form of the usual tone arm and reproducer are mounted for contacting with and reproducing the sound from the record in the usual manner, the same not being specifically illustrated in the drawing. Furthermore, drive mechanism is applicable for rotation of the turntable in conjunction with an automatic record changing mechanism, not illustrated herein.

The turntable is provided with a hub 16 having a downwardly extending spindle 17 which extends through the bearing 18 on which the hub is supported for rotation. Said bearing is mounted in

the fixed supporting plate 19 through which said spindle extends. The lower end of the spindle extends through a lower bearing 20 and is keyed to a cone-shaped driven member 21 in which are loosely mounted a plurality of ball bearings 22, 5 said ball bearings bearing against the periphery of the driving member 23. The member 23 is supported for rotation in the ball bearings 24 and has a downwardly extending drive shaft 25 supported for rotation in the bearing 26. The shaft 10 25 is operatively connected with the driving motor 14.

Slidably mounted on the spindle 17 and carrying the bearing 20, there is a cone-shaped ball race 27 adapted to engage and ride upon the 15 balls 22 about the outer surface of the driven member 21. By means of this arrangement, the balls 22 are carried in suitable recesses in the periphery of said driven member while they engage and roll about the peripheral surface of the 20 driving member 23. On the opposite side of the driven member, said balls engage the inner peripheral surface of the ball race 27.

Slidably mounted on the spindle 17 intermediate said ball race and the supporting plate 19, 25 there is provided a clutch member 28 having a peripheral groove 29 into which the free end of the lever 30 extends, said lever being fulcrumed to the frame at 31 extending below the base plate 10 beyond the periphery of the turntable and record 13. A suitable operating handle 32 is mounted upon a connecting rod 33 in such manner that when the handle 32 is elevated, it forces the clutch downwardly, and when said handle is pushed down, it forces the clutch upwardly. Said clutch is provided with an upwardly extending pin 34 adapted to extend into a recess 35 formed in the supporting plate 19. 30 35

The clutch is also provided with a downwardly 40 extending pin 36 adapted to extend into or through an opening 37 in the race 27 and into a corresponding opening 38 in the driven member 21. When the clutch is forced upwardly, the pin 36 is drawn out of the opening 38 in the driven member 21 and the pin 34 extends into the recess 35 of the supporting plate 19. Upon the clutch member being lowered, said pin 34 is released from the recess 35 while the pin 36 extends through the ball race 27 and into the driven 50 member 21.

In operation, the shaft 25 is so geared to the motor 14 as to be driven at substantially 78 R. P. M. When it is desired to rotate the record at that speed, the handle 32 is elevated so as 55

to lower the clutch member 28. The clutch member will then be free to rotate with the spindle 17 and the pin 36 of said clutch member will interlock the ball race 27 and driven member 21. 5 thus said driven member will be directly driven by the shaft 25 at 78 R. P. M. through the direct contact between the driving member and the balls 22 which are held, frictionally prevented from being rotated, by the ball race 27 which is locked 10 to said driven member 21. Thus, in this position, there will be a direct drive from the shaft 25 to the turntable. When it is desired to rotate the turntable at a lesser speed, or 33½ R. P. M., the handle 32 is pushed downwardly so as to elevate 15 the clutch member 28, locking the same with the stationary supporting plate 19 through the medium of the pin 34.

Thus, said clutch member will be held stationary and will also hold stationary the ball 20 race 27 through the medium of the pin 36. The pin 36, however, will have been retracted from the driven member 21 so that said driven member and ball race will be free to rotate relative 25 to each other. In this position, the driving member 23, instead of directly driving the driven member 21 through contact with the stationary balls, will cause said balls to rotate about the ball race 27 carrying the driven member with them, whereby the driven member will rotate at 30 a speed intermediate the speed of the driven member and the stationary ball race. A given speed may be obtained by the proper relation and dimensions of the members and balls, and as shown herein, approximately 33½ R. P. M.

35 From the foregoing, it will be observed that with a record adapted for reproduction at 78 R. P. M., the operator needs only to raise the handle 32 and with a record adapted to be reproduced at 33½ R. P. M., the operator need only 40 lower said handle. While specific R. P. M. have been above mentioned, it will be understood that substantially any two speeds of rotation may be obtained as desired.

The invention claimed is:

1. In a phonograph, the combination of a base plate, a turntable located above said base plate and adapted to rotate records of different reproducing speeds, and turntable rotating mechanism 5 located below said base plate, said mechanism comprising a motor for driving said turntable, a shaft driven by said motor at a predetermined speed having a driving member on the end thereof, a spindle connected with said turntable having 10 a driven member mounted thereon, said driven member being adapted to embrace said driving member, a stationary support for said turntable and spindle, a plurality of balls mounted for rotation in said driven member adapted to be engaged and rotated by said driving member, a ball race adapted to be locked with said balls and driven member for causing said driven member to be directly driven therethrough and unlocked therefrom to provide a ball race for said balls 20 for obtaining a slower speed, a clutch member for locking said race with said driving member while releasing it from the support when said clutch is in one position and when in the other position locking the same with said support while 25 releasing it from said driven member, and manually operable means extending through said base plate for selectively positioning said clutch in either of said positions.

2. A phonograph of the type including a motor 30 board, a conventional motor thereunder, a driving spindle driven therefrom and protruding above the motor board, a turntable on that portion of said spindle which is above said motor board and adapted to be driven by said spindle at 35 the rotary speed of the latter, a friction driven speed reducing transmission of definite ratio for driving connection between the spindle and the turntable and means extending through said motorboard for placing said transmission at will 40 into or out of operative connection.

EDWARD E. COLLISON,
EMIL NYMAN.
